CLAIM

The ornamental design for a fence stretching device, as shown and described.

DESCRIPTION

FIG. 1 is a perspective view of a fence stretching device with the adjustment arm inserted crosswise showing my new design;

FIG. 2 is another perspective view of the fence stretching device thereof, with the adjustment arm inserted lengthwise; FIG. 3 is a front perspective view of the fence stretching device with the adjustment arm removed;

FIG. 4 is a rear perspective view thereof;

FIG. 5 is another perspective view thereof;

FIG. 6 is a bottom view thereof, the top view being a mirror image of the bottom view;

FIG. 7 is a front view thereof;

FIG. 8 is a rear view thereof;

FIG. 9 is a right side view thereof, the left side view being a mirror image of the right side view;

FIG. 10 is a perspective view of the adjustment arm portion of the fence stretching device;

FIG. 11 is a bottom view thereof, the top view being a mirror image of the bottom view;

FIG. 12 is a front view thereof;

FIG. 13 is a rear view thereof; and,

FIG. 14 is a right side view thereof, the left side view being a mirror image of the right side view.
